UNITED STATES PATENT OFFICE.

BURNHAM C. STICKNEY, OF ELIZABETH, NEW JERSEY, ASSIGNOR TO UNDERWOOD COMPUTING MACHINE COMPANY, OF NEW YORK, N. Y., A CORPORATION OF NEW YORK.

TYPE-WRITING MACHINE.

1,286,827.

Specification of Letters Patent.

Patented Dec. 3, 1918.

Original application filed January 5, 1915, Serial No. 556. Divided and this application filed January 5, 1917. Serial No. 140,820.

To all whom it may concern.

Be it known that I, BURNHAM C. STICKNEY, a citizen of the United States, residing in Elizabeth, in the county of Union and 5 State of New Jersey, have invented certain new and useful Improvements in Type-Writing Machines, of which the following is a specification.

This invention relates to an improvement 10 in typewriting mechanism and more especially to means for enabling a typewriter carriage, as it travels to determine different zones or major columns, and change the character of printing so that digital items of 15 different import in the several columns may be distinctly printed. This case is a division of my application No. 556, filed January 5, 1915.

In writing columns of figures of different 20 import, as, for example, debit and credit items, it is often desirable that the worksheet when finished be self-explanatory; that is, that the debit and credit items be printed differently, so that one set of items 25 will stand out from the other. In the present embodiment of the invention, this is done by providing the digit type-bars with two sets of digits, distinctive one from the other. When it is desired to print in a 30 column one set of items, such as credit items, the lower-case digit types are used. When it is desired to print another class of items, such as debit items, the upper-case digit types are used. The shift from one to the 35 other is controlled automatically from the carriage itself by the tabulating stops or similar stops or tappets operating the usual case-shift frame. The character of printing-controlling stops is made so that they 40 can be reversed from one position to the other. In one position they are effective as controlling the character of the printing and in the other position they are ineffective. They may also be adjustable along the carriage so as to determine the particular location 45 of the zones or major columns in which they become effective.

Other features and advantages will hereinafter appear.

50 In the accompanying drawings, Figure 1 is a vertical transverse section taken from front to rear with parts omitted to simplify the showing.

Fig. 2 is a skeleton perspective view of the

case-shift mechanism showing one of the 55 characters of printing-controlling stops in the act of shifting the case-shift frame to upper-case position.

Fig. 3 is a detail view of a group of the 60 type-heads showing that each of the digit type-bars has two distinctive sets of characters of the same value, in this case, the distinction is merely one of size, the lower-case being small numbers and the upper-case being large numbers or capitals.

Fig. 4 is a view similar to Fig. 3 of a modified form of the invention, in which the distinction between the digit type is one of configuration, the lower-case being in normal Arabic and the upper-case being in 70 italics.

Alphabet keys 1 and numeral keys 2 depress key-levers 3, to rock bell cranks 4, to swing type-bars 5 up rearwardly so as to strike, through a printing ribbon 6, a work-sheet carried by the platen 7. It will be noted in passing that the numeral type-bars 5 are provided with two sets of types 8 and 9, the former being for printing lower-case characters, and the latter for printing upper-case characters. These two sets of types distinguish from each other in outlines or other features, so that when writing with one set, a characteristically written number will be in evidence, which will be 85 clearly distinct from the numbers afforded when writing with the other set. The distinction may be one of magnitude, as in Fig. 3, where the lower-case characters are small and the upper-case characters are large; or 90 the distinction may be one of conformation, as in Fig. 4, where the lower-case characters are normal Arabic and the upper-case characters italics.

The platen 7 is mounted on a carriage 10, 95 which travels on ways 11 under the control of an escapement mechanism 12, which may include a rack 13, pivotally mounted on the carriage and engaging a pinion 14 controlled by an escapement wheel 15, which in turn is controlled by fixed and movable dogs 15^a. The dogs 15^a are oscillated into alternate engagement with the escapement wheel 15, by a universal frame 16 operated by heels 17 on all of the type-bars 5.

100 In order to enable the change in printing from the lower-case types 8 to the upper-case types 9, the platen 7 is mounted in a

frame 18, which in the present instance, as is common in Underwood typewriting machines, is vertically adjustable so as to offer the line of print of the work-sheet on the 5 platen, normally, to the lower-case types 8, and on other occasions to the upper-case types 9.

To effect the movement of the platen 7 and its frame 18, the latter is supported by 10 a roller 19, which travels on a shift rail 20 supported by a shift frame 21 which is mounted to swing about a shaft 22. The shift frame 21 may be rocked manually to effect a change in case or character of printing, by one or more shift keys 23. In the 15 present instance, two are shown, one for a temporary shift and the other for a semi-permanent shift. These shift keys 23 are each provided with an upwardly-extending 20 arm 24, which engages in back of the shift frame 21, and rocks the same to elevate the platen 7 and its frame 18.

The carriage 10, which, as stated above, obtains a step-by-step advancing movement 25 at the striking of any of the keys 1 or 2, under the control of the escapement mechanism 12, also may have a major or jump movement to change quickly from one zone or major column to another. For this purpose there is provided a tabulating mechanism, which may include decimal tabulating 30 keys 25, which when depressed, rock key-levers 26 to thrust up plunger stops 27 into the path of carriage stops 28, which may be 35 adjustably mounted at letter-space intervals along a rack 29 carried by the carriage 10. To effect the release of the carriage at the operation of the tabulating mechanism, a lever 30 universal to all of the plunger stops 40 27, may be rocked at the operation of any one thereof, to draw down on a link 31, so as to rock a lever 32, which bears at its forward end, a roller 33 underlying the rack 13, so as to lift the latter out of mesh with 45 the controlling escapement pinion 14.

It is often desirable to make the typewriting distinctive for writing digital items of different import, as for example, credit and debit items. For this purpose there are 50 provided two different sets of type on the numeral type-bars. Lower-case type being used for one set of items, such as credit items, and the upper-case type for another set of items, such as debit items. Either 55 form of the types 8 and 9, may be used as shown in Figs. 3 and 4. In order that the carriage itself may control the change in the character of printing automatically according to a predetermined plan character- 60 istic of the work being done, one of the stops 28 or any other tappet, which may or may not coöperate with plunger stops 27 is formed and positioned to come into play, on 65 entering a zone or column in which it is desired to write debit or upper-case items. In 70

the present instance, the special tappet or stop 28 controlling upper-case writing, is provided with an elongated foot or extension 34, which when the tappet or stop is located for a credit zone will be in its upper-most position as indicated at 28^a in Fig. 3 and ineffective. When, however, a debit or special item column is being determined, the extension will be located in its lower position as indicated at 28^b, Fig. 3, in which position 75 it will determine the writing of upper-case characters. To do this, the stop 28 with its long foot is properly positioned along the carriage 10 at such a point as will bring it into play when the work-sheet on the carriage 80 brings to the printing point the columns at which it is desired to write debit or upper-case items. At such time the stop 28^b will come into engagement with a cam edge 35 on a zone-controlling bar 36 having 85 an extent or effective length corresponding to the number of letter-spaces or digital columns desired in the debit column or zone. The bar 36 when so engaged will be depressed downwardly and held depressed during 90 the writing of the digits for the zone or major column. The depression of this bar forces down a link 37 connected thereto, which in turn swings downwardly a rock arm 38 fixed on the shaft 22 which forms a 95 pivotal mounting for the case-shift frame 21. This then will cause the case-shift frame 21 to rock forcing upwardly the shift rail 20, so that the platen frame 18 will be raised to its upper-case position when the upper- 100 case digit type 9 will be effective to print.

It will thus be seen that a series of columns or zones representing selectively debit and credit items may be distinctively printed according to a pre-arranged plan, so that 105 the operative can tell at a glance which are the debit items and which are the credit items. The distinctive typewriting may be used for any other purpose and is substantially automatic after the stops or tappets 28 110 have been once set or adjusted. For example, zones can be varied in width by placing two stops 28 with their tails 34 at such a distance apart that one becomes effective on the cam 35 before the other releases it. 115 Thus there may be a long central zone, in which the case is automatically shifted to upper, with a lower case zone at each end of the typewriter carriage travel. Again, with another setting of the stops 28, there 120 may be two separated zones, in which the case is automatically shifted to upper.

Variations may be resorted to within the scope of the invention, and portions of the improvements may be used without others. 125

Having thus described my invention, I claim:

1. The combination with type actions having two sets of distinctive types, of a platen coöperating with said types, a traveling car- 130

riage, a case-shift frame for determining which of said types shall be in action, and controlling means adapted to be set for operating said case-shift frame from said carriage a plurality of times in a single traverse thereof.

2. The combination with a typewriter carriage, of type-actions coöperating with said carriage and having duplicate sets of figure types to print different sets of items distinctively one from the other, and means effective during a single traverse of said carriage, for causing repeated predetermined relative shifts between the carriage and the figure types.

3. The combination with a carriage movable into a plurality of column-printing zones during a single traverse thereof, of type actions having a plurality of sets of types coöperating with said carriage to print on a work-sheet carried by said carriage, a case-shift mechanism for determining which set of types shall print, a tabulating mechanism for determining column selections in the travel of said carriage, stops performing two functions, coöperating with said tabulating mechanism to determine the column or zone selection, and connected to control said case-shift mechanism to determine the character of printing to correspond with the particular zone or column selected, and means for restoring the case-shift mechanism as the carriage concludes its movement through a zone.

4. The combination with type actions having a plurality of different case characters, of a platen having longitudinal movement relative to said type action to effect step-by-step printing and also having a movement transverse to the longitudinal movement to effect a change in the case or character of printing, and means for enabling one of said movements to cause the other of said movements, said means also including devices to vary the length of zone over which said change is effective, irrespective of the position of the zone.

5. The combination with type actions having a plurality of case characters to enable different kinds of printing, of a platen having a traveling movement to enable character by character printing of said type action, and having a case-shift movement to enable selections in the character of printing, and automatic means controlled by the longitudinal movement of said platen and effective during a single traverse thereof, for causing repeated case-shift movements of said platen, so that each of a plurality of distinctive types of printing for different positions along said platen may be automatically had in each of a plurality of columns.

6. The combination with a carriage having a traveling movement to determine different zones or columns as well as being

capable of step-by-step feeding, of type-actions coöperating with said carriage and having a plurality of sets of types to give distinctive typewriting at different times, shiftable means to bring a certain one of said sets into use, a series of elements individually adjustable along the path of travel of said carriage, and means effective during a single traverse of the carriage to enable each of said adjustable elements both to locate a column or zone and also to operate said shiftable means, to change the character of printing in the located zone; means being provided for restoring the shiftable means to normal position at the completion of writing in a zone.

7. The combination with a carriage, of a platen, type actions having a plurality of different sets of types coöperating with said platen to print, case-shift mechanism enabling a change in the type of printing, a cam extending over a zone for operating said case-shift mechanism, and one or more tappets carried by said carriage for automatically operating said cam by travel of said carriage, said tappets adapted to be set so as to vary the length of the zone over which the case shift is effective.

8. The combination with a carriage, of a platen on said carriage, type actions having a plurality of different case characters to enable different types of printing, said carriage and said platen having a traveling movement to bring different letter-spaces of the work-sheet carried thereby into printing opposition to said type actions, case-shift mechanism for determining different types of printing by said type actions, a linkage connected to operate said case-shift mechanism, a cam bar extending over a plurality of letter-spaces connected to operate said linkage, and one or more tappets on said carriage arranged to actuate said cam bar to independently vary the position and number of letter-spaces over which the cam bar is effective.

9. The combination with a carriage, of a platen carried by said carriage, type actions coöperating with said platen having a plurality of different case of characters, case-shift mechanism for enabling the change of the case of printing, a linkage connected to operate said case-shift mechanism, a cam bar connected to operate said linkage, and one or more tappets mounted on said carriage to coöperate with said cam bar to operate said case-shift mechanism, said cam bar having an effective length corresponding to a plurality of letter-spaces or digit columns as written by said type actions.

10. The combination with a traveling carriage, of type-actions arranged to strike the work-sheet carried by the said carriage at a common printing point, duplicate sets of figure types having a different significance

for printing at that point, and means controlled by the position of the carriage in its travel for determining which set shall print.

11. The combination with a letter-feeding carriage, of a platen mounted on said carriage, type-actions coöperating with said platen having a plurality of different case characters, case-shift mechanism for enabling a change in the case of printing, unsymmetrical tappets separately settable along said carriage, a cam extending over a plurality of letter-spaces in the travel of said carriage and adapted to be swung by said tappets, said tappets being effective or ineffective according to the location of their major sides, and connections whereby the case shift is effective when the cam is swung by a tappet, the connections being such that the case shift is ineffective when no tappet is effective on the cam.

12. The combination with a traveling carriage, of duplicate sets of figure types having a different significance for printing on said carriage, a cam adjacent the travel of said carriage and extending along a substantial part of the travel thereof, a rack bar forming part of said carriage, stops settable on said rack bar, certain of said stops having extensions to coöperate with said cam, connections whereby when said cam is in its normal position one of said sets of types is effective to print, and when shifted by a stop from its normal position another of said sets is effective to print, and a tabulating device for positioning said carriage by said stops.
